CONTROL APPARATUS

Ernest M. Miller, Minneapolis, Minn., assignor to
 Minneapolis-Honeywell Regulator Company,
 Minneapolis, Minn., a corporation of Delaware

Application April 21, 1930, Serial No. 446,160

6 Claims. (Cl. 158—28)

This invention relates to burner apparatus controlling means. An important object is to provide means adapted to respond to production of flame at the burner, and when in one position to permit initiation of burner apparatus operation, including ignition, and when in another position to maintain burner motor operation but discontinue ignition, and further adapted to move from the burner operation maintaining position to another position in a predetermined period of time, and at the end of this time to condition the apparatus for re-ignition.

Another object is to provide means which, when flame is absent, permits the burner apparatus to be started, and when flame is present maintains burner operation, and which is capable of timing the interval, between a shut-down of the apparatus normal or otherwise, and a re-energization of the same.

Features and advantages of the invention will be set forth in the description of the drawing forming a part of this application, and in said drawing:

Figure 1 is a diagram of the system in its initial position before energization, or before a call for heat by the room thermostat, and

Figure 2 is a perspective view of the combustion responsive switch.

Some of the principal parts of the apparatus will be now referred to, but for sake of brevity the electrical connections will be referred to only in the description of the operation.

Letters R, B, W, represent the elements of a double contact thermostat adapted to start the apparatus when sufficiently cold and to stop the apparatus, under normal conditions, when sufficiently hot. Numeral 16 indicates any suitable form of ignition. It will be understood that suitable fuel supply and control means is provided, although not shown. The term "burner apparatus", as used herein, includes the combustion chamber, not shown, the burner motor 17, the ignition 16, and the fuel supply and control means. The present invention is applicable to any form of apparatus including the elements referred to.

The numeral 3 indicates the coil of a relay, referred to as relay No. 1, and the numeral 4 indicates the coil of a similar relay, referred to as relay No. 2. Energization of relay No. 1 establishes a starting circuit for it, and energizes ignition means and burner motor. Elements 5 and 6 represent respectively the switch and the heating coil of a thermal safety device herein referred to as a thermal safety switch, the function of which is to render the whole apparatus inoperative (so that it cannot be restarted automatically until after inspection and repair) if ignition is not produced at the end of a predetermined period.

An important element of this system is the

device generally indicated at 7 which is referred to herein as a pyrostat. This device includes the spaced contacts C and H, and the element 8 movable between them. The movement of the element 8 between the contacts C and H is timed. 65 In the device as used, this timing period can be varied. The motion of the element 8 from its initial position shown in the drawing is produced by thermal means such as a thermostatic spiral ribbon 8^a, controlling rod 8^b, to which contact arm 8 is secured. This arm is suitably insulated as at 8^c. The contacts H and C are shown as widely spaced and each is properly insulated from plate 8^e. One end of the spiral ribbon 8^a is secured to the rod and the opposite end is secured to a tubular extension 8^d carried by plate 8^e. This device is affected by the production of flame at the burner. On production of flame the element 8 leaves the contact C and moves toward the contact H. The device, of course, is properly placed to be affected 80 by the production of flame and in practice is generally arranged in the stack. It is necessary for the element 8 to close the contact C before the apparatus can be started and this is one of the important features of the invention. Another 85

important feature is that an appreciable amount of time is required for element 8 to move from element H to element C upon flame extinguishment, so that before the apparatus can be restarted by closing the contact C through element 90 8, the accumulated gases in the combustion chamber may have time to dissipate. The switch arm 8 may be thermally controlled by any suitable device, providing it is so constructed as to properly time the motion of the arm from H to C and 95 from C to H. Any suitable combustion responsive double contact switch may be used, and there is no intention to be limited to any specific structure for this element. It is merely noted that the structure and arrangement and proportioning 100 of the parts is such that upon cessation of combustion contact of 8 with C is delayed for the proper time interval.

Operation

The operation of the device is as follows: Suppose a call for heat and closure by R of contacts B—W. Relay No. 1 is energized through the following circuit: one side of the secondary 2 of the transformer, conductor 20, contact 5 of the safety 110 switch, conductor 21, W, R, B, 22 to C of the pyrostat, 8, 23, contact 14, 25 of relay No. 2 (while relay is de-energized), heating coil 6 of the thermal safety switch, 26, coil 3 of relay No. 1, 27, 28 to the opposite side of secondary of 115 transformer 2. On energization of coil 3, contacts 10, 11 and 12 are closed. Closure of contact 10 establishes a holding circuit for relay No. 1 as follows: 2, 20, 5, 21, W, R, 30, 10, 31, 14, 25, heating coil 6, 26, 3, 27, 28 to 2. It is now no longer 120

necessary (in order to hold relay No. 1 closed) for the circuit to pass through B, 22, C, 8 and 23, therefore when contact C opens due to production of flame, relay No. 1 remains energized. Closure 5 of contact 11 energizes the motor through the following circuit: hot line 35, 37, contact 11, 38, 39, 40, motor 17, 41 to ground line 36. The closure of contact 12 energizes the ignition through the following circuit: hot line 35, 37, contact 11, 38, 10 contact 12, 42, ignition means 16, 43 to the ground line. Ignition is now active and a trial ignition period begins, and if not successful at the end of a predetermined period switch 5 will open as the result of continued heating of coil 6, and the 15 apparatus will be rendered inoperative, as a result of de-energization of coil 3 of relay No. 1. In practice, if this happens, the apparatus cannot be restarted until after inspection, repair and manual operation of a switch, not herein shown but 20 associated with the thermal safety switch and in a manner well known in this art.

If flame is produced before the end of that predetermined period for which switch 5 is set to open, element 8 will move in the direction of the 25 arrow and make contact at H, and upon making of this contact, relay No. 2 will be energized through the following circuit: 2, 20, 5, 21, W, R, 30, 10, 31, 23, 8, H, 45, coil 4 of relay No. 2, 46, 28 to 2. However, on energization of relay No. 2, 30 the circuit of coil 3 is broken at contact 14 and relay No. 1 falls out opening contact 12 and interrupting ignition. At the same time, contact 15 is closed and motor operation is continued through the following circuit: 35, 37, 50, 15, 51, 35 40, motor 17, 41 to 36.

Normally the burner apparatus now operates until R opens at W in which case relay No. 2 opens and the apparatus assumes the initial position shown in the figure, with the exception that 8 is 40 making contact at H. Under these conditions, the apparatus cannot be again started until 8 has moved to contact C which is in the starting circuit and which controls the starting circuit. This is a feature, as is also the provision of a 45 definite timed period, before contact is again made at C. The apparatus which controls the element 8 can be timed and its time period can be adjusted. Therefore, it will take the element 8 a predetermined amount of time to move from H to C. This period is such that any explosive 50 gases in the combustion chamber will have been dissipated before ignition means is again made active. This delayed return to starting position safeguards against the possibility of explosion 55 due to accumulation of vapor, if the flame is extinguished prematurely or if the burner is started and stopped in quick succession, due to tampering with the thermostat. A safety interval of approximately ninety seconds is provided 60 and this is controlled by the flame responsive device; a feature of the invention. An advantage is that the motor is shut down immediately on flame failure due to the opening of relay No. 2. Thus the device herein referred to as a "pyrostat" 65 is also a timer, and must break its contact each time the burner is shut down. If the contact H should stick or become short-circuited accidentally or intentionally the burner cannot be started because in that case, either contact C or contact 14, or both would not be closed. This 70 delayed return to starting position by the element 8 is a very important feature because the burner cannot be started and stopped in quick succession and thereby develop a hazardous condition. Of course, it will be understood that in order to get

a start when contact C is closed, the thermostat must be making contact at W-B, and the apparatus must be otherwise electrically and mechanically fit.

It will be noted that the starting circuit for 80 relay No. 1 passes through contact C of the pyrostat, contact 14 of relay No. 2 (before this relay is energized) and through heating coil 6 of the thermal safety switch. Thus, initially, the thermal safety switch is always energized and relay No. 2 must be open and contact C of the pyrostat closed before this can be accomplished. The closing of relay No. 1 establishes a holding 85 circuit for itself through contact 10, and since contact 14 is at this time closed, this circuit can be maintained without passing through contact C.

Production of flame at the burner closes No. 2 relay, opens the holding circuit for No. 1 relay, 90 contact 11 is opened and the ignition means is de-energized, motor contact 12 is also opened, but the motor remains energized because contact 15 is closed. By the closure of relay No. 2 its own holding circuit is established through contact 13 controlled by it, and through contact H of the 100 pyrostat. On closure of No. 2 relay, the heating coil 6 and relay No. 1 are de-energized.

On flame failure, or on a call for less heat by the thermostat, relay No. 2 falls out due to the breaking of the holding circuit at H; 8 moves from 105 H to C and at the end of a predetermined period, the starting circuit for relay No. 1 is again made. If the thermostat is closed at B-W and if thermal safety switch 5 is closed, relay No. 1 is again energized, and if flame is not successful at the end 110 of a predetermined period, thermal safety switch 5 is opened and the plant is shut down in the usual manner and cannot again be operated automatically until after adjustment and repair and the manual closing of the thermal safety switch. 115

Although the general combination with the thermal safety switch, including the elements 5 and 6, is also claimed, claim is made to combinations in which this switch is omitted, for it is evident that by removing the elements 5 and 6, 120 and connecting lines 20 and 21, and lines 25 and 26, the timing function by the flame responsive device 7 can be performed.

I claim as my invention:

1. A device of the class described comprising 125 a first relay having a holding contact, a second relay controlling first and second contacts to close the first when the relay is de-energized and to open the first and close the second when the relay is energized, a switch responsive to variations in 130 physical conditions and having two contacts operable to close the first contact on sufficient physical variation in one direction, and to open the first contact and close the second on sufficient variation in an opposite direction, the variation of the 135 physical condition in the first direction resulting in opening the second contact a timed interval before closing the first contact, an energizing circuit for the first relay which is dependent on closure of the first contacts respectively of said 140 second relay and said switch, a holding circuit for the first relay dependent on closure of the holding contact of said first relay and on closure of said first contact of the second relay, an energizing circuit for the second relay dependent on closure 145 of the holding contact of the first relay and on closure of the second contact of the switch, and a holding circuit for the second relay dependent on closure of the second contact of said second relay and the second contact of said switch. 150

2. In a burner control system for an igniter and a fuel control means, a first relay operable to control said igniter and fuel control means and having a holding contact, a second relay operable to control said fuel control means only and controlling first and second contacts to close the first when the relay is de-energized and to open the first and close the second when the relay is energized, a switch responsive to combustion conditions, having two contacts and operable to open the first contact and close the second on combustion production and to open the second contact a timed period before closing the first contact on combustion failure following successful ignition, an energizing circuit for the first relay which is dependent on closure of the first contacts respectively of said second relay and said switch, a holding circuit for the first relay dependent on closure of the holding contact of said first relay and on the closure of said first contact of the second relay, an energizing circuit for the second relay dependent on closure of the holding contact of the first relay and on closure of the second contact of the switch, and a holding circuit for the second relay dependent on closure of the second contact of said second relay and the second contact of said switch, and a safety timer switch adapted to render the system inoperative if flame is not produced at the end of a timed period, including a heater for controlling the timer switch, said timer switch being in all control circuits and said heater coil being in the energizing and holding circuits of said first relay.
3. A first relay having a holding contact, a second relay controlling first and second contacts to close the first contact when the relay is de-energized and to open the first and close the second contact when the relay is energized, a thermally operable switch device having two contacts operable to open a first and close a second contact on temperature rise and to close the first contact a timed period after opening the second contact on temperature fall, a starting circuit for the first relay including the first contact of the thermally operable device and the first contact of said second relay, a holding circuit for the first relay including therein the holding contact of said first relay and said first contact of said second relay, an energizing circuit for said second relay including therein the holding contact of the first relay and said second contact of said thermally operable device.
4. Ignition means, fuel control means, a first relay operable to control ignition and fuel means and having a holding contact, a second relay operable to control the fuel means and controlling a double contact switch to close a first contact when the relay is de-energized and to open a first and close a second contact when the relay is energized, a device controlled by combustion conditions having two contacts and operable to open a first and close a second contact on combustion production and on combustion failure to open the second contact a timed period before closing the first contact, a starting circuit for the first relay including therein said first contact of the combustion responsive device and the first contact of the second relay, a holding circuit for the first relay including therein the holding contact of said first relay and said second contact of said second relay, an energizing circuit for said second relay including therein the holding contact of said first relay and said second contact of said second relay, and a safety timer switch responsive to the disappearance of the flame contacting the second contact after the elapse of a time period; first and second relay switches, said first relay switch operating when energized to energize said igniter and motor, the operating circuit of such relay having said second contact and a contact of said second relay switch therein, said relay switch operating when energized closing a second holding circuit including said second relay switch contact but independent of said second contact; said second relay switch, having an operating circuit including said first contact, said second relay switch operating when energized to open said contact in the holding circuit of said first relay switch to de-energize the same and to close a second circuit for the burner motor.
5. In combination, a burner apparatus including an electric burner motor and an electrically operated igniter, an electrical control system therefor including a switch device responsive to flame at the burner and having a switch arm and spaced switch contacts, the switch arm contacting a first contact when there is a flame and, on disappearance of the flame contacting the second contact after the elapse of a time period; first and second relay switches, said first relay switch operating when energized to energize said igniter and motor, the operating circuit of such relay having said second contact and a contact of said second relay switch therein, said relay switch operating when energized closing a second holding circuit including said second relay switch contact but independent of said second contact; said second relay switch, having an operating circuit including said first contact, said second relay switch operating when energized to open said contact in the holding circuit of said first relay switch to de-energize the same and to close a second circuit for the burner motor.
6. In a burner control system, a first relay having a holding contact which is closed when said relay is energized, a second relay controlling first and second contacts to close the first when the relay is de-energized and to open the first and close the second when the relay is energized, switching means responsive to combustion conditions having a cold switch and a hot switch and operable to open the cold switch and close the hot switch on establishment of combustion and to open the hot switch a timed period before closing the cold switch on cessation of combustion, a safety timer switch including an electrical heating element and adapted to render the system inoperative if said heating element is operatively energized for a predetermined length of time, a fuel control device, ignition means for igniting the fuel, circuit connections for initially energizing said first relay and heating element controlled by the first contact of the second relay, the safety switch, and the cold switch in series, circuit connections for maintaining energization of said first relay and heating element controlled by the holding contact of the first relay, the safety switch and the first contact of the second relay in series, an energizing circuit for the second relay controlled by the holding contact of the first relay and said hot switch in series, a holding circuit for said second relay controlled by said second contact of the second relay and said hot switch, and connections between said first relay, second relay and fuel control device for operating the latter to initiate supply fuel upon energization of said first relay and to maintain the supply of fuel upon energization of said second relay.
